Patented July 17, 1973

227,734

LOCK SET END PLATE

Nicholas Giandomenico, West Covina, Calif., assignor to
Acme General Corporation, Monrovia, Calif.

Filed Jan. 25, 1971, Ser. No. 109,747

Term of patent 14 years

Int. Cl. D8—06

U.S. Cl. D8—138

FIG. 1

FIG. 3

FIG. 2

FIG. 1 is a perspective view of a lock set end plate constructed according to principles of this invention shown in the environment of use as the outer face of the knob of the lock set broken lines for the door knob are for illustrative purposes only;

FIG. 2 is an end view of the lock set end plate; and
FIG. 3 is a cross-section through the end plate of FIGS. 1 and 2.

I claim:
The ornamental design for a lock set end plate, as shown and described.
